(57) **CLAIM**

The ornamental design for a combined earphone and watch,
as shown and described.

DESCRIPTION

FIG. 1 is a front perspective view of an earphone, of a
combined earphone and watch, showing my new design, the
earphone is shown separately for ease of illustration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of an earphone, of the
combined earphone and watch thereof, the earphone is
shown separately for ease of illustration;

FIG. 10 is a rear perspective view thereof;

FIG. 11 is a front view thereof;

FIG. 12 is arear view thereof;

FIG. 13 is a left side view thereof;

FIG. 14 is a right side view thereof;

FIG. 15 is a top view thereof;

FIG. 16 is a bottom view thereof;

FIG. 17 is a front perspective view of the watch, of the
combined earphone and watch, the watch is shown sepa-
rately for ease of illustration;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a front perspective views of the watch, of the
combined earphone and watch in an open position thereof;

FIG. 26 is a front perspective view of the combined ear-
phone and watch in an open position thereof; and,

FIG. 27 is a front perspective view thereof, in an open
position.

1 Claim, 27 Drawing Sheets
